UNITED STATES PATENT OFFICE.

EDWARD DEGNAN, OF KENOSHA, WISCONSIN.

WEARING-APPAREL.

1,358,940.

Specification of Letters Patent. Patented Nov. 16, 1920.

Application filed April 21, 1919. Serial No. 291,656.

To all whom it may concern:

Be it known that I, EDWARD DEGNAN, a citizen of the United States, residing at Kenosha, in the county of Kenosha and 5 State of Wisconsin, have invented certain new and useful Improvements in Wearing-Apparel, of which the following is a specification.

This invention relates to improvements 10 in wearing apparel and more particularly to underwear of that class known as athletic underwear. One object of the invention is to provide a garment that can be manufactured with the greatest economy in 15 the use of goods, the goods being cut so that what is ordinarily wasted as trimmings can be utilized in the manufacture of the garment. Where hundreds or thousands of garments are cut every day a saving 20 in time and a saving in goods, of substantial proportions, is effected. The invention consists in the combination and arrangement of parts to be hereinafter fully described, pointed out in the appended 25 claims and illustrated in the accompanying drawing which forms a part of this specification and in which—

Figure 1 is a plan view of the garment partly finished.

30 Fig. 2 is a section, enlarged, taken on line 2—2 of Fig. 1.

Like reference characters denote corresponding parts in both views.

The garment proper is formed of the lateral body pieces 1, 2 having the straight-edge portions 3, 4 and contiguous thereto the edges of said pieces are formed with the recesses 5, 6, said pieces being united adjacent said recessed portions by the insert 40 7 to which they are sewed, said pieces, further, being formed with the recessed portions 8, 9 and with the recessed portions 10, 11 to form the arm pieces 12, 13. The insert 7 is formed of knitted goods along its

inner edge, its opposite edge being formed 45 with the recessed portions 14, 15 that register, respectively, with the recessed portions 10, 11 of the body pieces 1, 2.

To the outer edge of the insert 7 a double or two-piece neck piece 16 is sewed along 50 the line 17, the said piece 16 being so placed that the grain of the goods runs opposite to the run of the grain in the insert 7 thus insuring greater wearing quality. The outer lateral edges of the body pieces 1, 2 55 are to be provided with buttons and button-holes so that said edges, when brought together about a person's body, can be secured together. The neck piece is formed entirely of material cut from the recessed portions 60 at the crotch 18 and at the recessed ends of the pieces 1, 2. The arm pieces are sewed to the neck piece to form the arm holes, and the portions 3, 8 and 4, 9 are sewed together to form the legs. 65

What is claimed is:—

1. A union garment comprising, a pair of body pieces formed with recessed portions, arm pieces formed on said body pieces, an insert connecting said body pieces 70 at the back, and a neck piece secured to said insert.

2. A union garment comprising, a pair of body pieces having their edges recessed, arm pieces, formed with recessed edges, integral with said body pieces at the back, an insert connecting said body pieces, and a two-piece neck piece secured to said insert in such manner that the grain of the two members runs in different directions. 80

In testimony that I claim the foregoing I have hereto affixed my signature in the presence of two subscribing witnesses.

EDWARD DEGNAN.
